UNITED STATES PATENT OFFICE.

JAMES H. ALEXANDER, OF PHILADELPHIA, PENNSYLVANIA, ASSIGNOR TO
THOMAS DEVLIN & CO., OF SAME PLACE.

DESIGN FOR A TRUNK-IRON.

SPECIFICATION forming part of Design No. 16,505, dated February 9, 1886.

Application filed December 19, 1885. Serial No. 196,235. Term of patent 7 years.

To all whom it may concern:

Be it known that I, JAMES H. ALEXANDER, a citizen of the United States, residing at Philadelphia, in the county of Philadelphia and State of Pennsylvania, have invented a certain new and useful Design for Trunk-Irons; and I do hereby declare the following to be a full, clear, and exact description of the invention, reference being had to the accompanying drawing, which forms part of this specification, in which the figure is a plan illustrating my design.

My design relates to the shape of the iron and to the configuration and ornamentation of the surface thereof; and it consists in such shape and ornamentation. Such ornamentation consists, essentially, of surface configuration in the form of a diamond-shaped or approximately diamond-shaped figure, the sides thereof being each composed of a series of short curves joined at their extremities, said figure having a circular center inclosing a cross or X, with radial lines extending from the circle to the sides of the diamond, and with such sides forming or inclosing triangular spaces.

Referring to the accompanying drawing, A designates the iron, the surface of which is configurated with a diamond-shaped or ap-

proximately diamond-shaped figure, B, each of the sides of which is composed of a series of short curves, b b, joined at their extremities. The figure B has a centrally-located circle, C, inclosing an X or cross, D. From the circle D there radiate lines E E of different lengths, the outer extremities of such lines meeting the sides of the figure B, and such lines and sides inclosing or forming triangular spaces e.

What I claim as my design is as follows:

The design for a trunk-iron herein described, 40 the same consisting of a diamond-shaped or approximately diamond-shaped figure, the sides of which are each composed of a series of short curves joined at their extremities, said figure containing a circle inclosing an X 45 or cross, with radial lines extending outwardly from said circle to the external figure, and with the sides of the latter forming or inclosing triangular spaces, substantially as shown and described.

In testimony that I claim the foregoing I have hereunto set my hand this 4th day of December, 1885.

JAMES H. ALEXANDER.
